UNITED STATES PATENT OFFICE.

DAVID FELIX BRODERICK, OF NEW BRITAIN, CONNECTICUT, ASSIGNOR OF
ONE-HALF TO LEWIS SPERRY, OF SOUTH WINDSOR, CONNECTICUT.

ELECTROPLATING APPARATUS.

No. 858,059.

Specification of Letters Patent.

Patented June 25, 1907.

Application filed August 10, 1906. Serial No. 330,046.

To all whom it may concern:

Be it known that I, DAVID FELIX BRODERICK, a resident of New Britain, in the county of Hartford and State of Connecticut, have 5 invented certain new and useful Improvements in Electroplating Apparatus; and I do hereby declare the following to be a full, clear, and exact description of the invention, such as will enable others skilled in the art to 10 which it appertains to make and use the same.

My invention relates to improvements in electro-plating apparatus and more particularly to dipping mechanism,—the object of the invention being to construct the apparatus 15 in such manner that the full extent of an endless carrier for the work, can be utilized in subjecting the work to the various baths employed in the art of electro-plating,—the apparatus being so constructed and operated 20 that the work to be plated can be started from a given point or station and made to return thereto, said work being deposited successively into the various baths during its travel from the starting station and back 25 again.

A further object is to provide an apparatus for the purpose stated, which shall be continuous in operation, simple in construction and effectual in the accomplishment of the 30 purposes for which it is designed.

With these objects in view, the invention consists in certain novel features of construction and combinations and arrangements of parts as hereinafter set forth and pointed out 35 in the claims.

In the accompanying drawings: Figure 1 is a side elevation of an apparatus embodying my improvements; Fig. 2 is a sectional view on the line $x-x$ of Fig. 1; Figs. 3 and 4 are 40 detail views showing the connection of the work holder with the carrier; Fig. 5 is a detail view illustrating the construction of the carrier chain; Fig. 6 is a detail sectional view illustrating the carrier chain, idle wheel 45 and work-holding bar of the carrier; Fig. 7 is a detail view showing the attachment of the contact brushes to the shank of the work holder; Fig. 8 is a view of the driving sprocket wheel.

1, 2 illustrate superposed platforms, which may be two floors of a building, and from each of these platforms (or the supporting timbers thereof), a series of hangers 3 depend. The hangers below each platform or floor are

arranged in pairs spaced apart laterally and 55 serve as supports for two pairs of stringers, 6. These stringers serve as supports for wheels, 4, 5, over which two endless carrier chains 7, 7, pass,—said carrier chains passing over the entire series of wheels on the upper and lower 60 stringers and through openings 8, 9 in the platform 2. The two carrier chains are connected at intervals by cross bars 10, which support work holders adapted to travel successively through a series of tanks 11 on the 65 platform 2 and then through a series of tanks 12 on a lower floor or platform 1, and finally back to the starting point.

In the drawings, I have shown four tanks located on the platform 2 and three tanks 70 located on the lower platform 12, although a greater or less number of tanks may be employed for containing the various baths which it may be desired to use.

The carrier (consisting of the two carrier 75 chains with the interposed cross bars 10), pass first over wheels 5 and then descend and pass about wheels 4, thus causing the work on the carrier to descend and pass through the first bath. The carrier then passed up 80 and over wheels 5 in order to raise the work over the dividing wall or space between two tanks, and then down again about wheels 4 to deposit the work in the next tank. As the carrier proceeds, it will pass over the wheels 85 4, 5 for the purpose of immersing the work successively in the various tanks on the platform 2, and it will then pass to the lower series of wheels 4, 5 and over them in the same manner, in order to immerse the work in the 90 baths in the tanks on the lower platform 1,—the work on the carrier finally reaching the starting point. The work may be removed from the carrier after passing through all of the baths, either at 13 on platform 1 or at 14 95 on platform 2. The work may be attached to the carrier at either 13 or 14, or it may be loaded at 14 on the upper platform 2 or at 13 on the lower platform 12 and, during its travel, the work will be treated in all the baths 100 necessary to accomplish electro-plating and the full extent of the carrier will be utilized.

The carrier may be driven by means of suitable gearing connected with the sprocket wheels 15.

Each carrier chain comprises two sets of links 16, 17 pivotally connected together by hinge pins 18, the members of the inner links

being spaced apart on the hinge pins by means of collars 19, which run on flanges 20 on the wheels 4, 5, while the links of the chain run at respective sides of the peripheral flanges 20, thus preventing lateral displacement of the carrier chains as they pass over the wheels 4, 5. The hinge pins of the carrier chains extend beyond the outer faces of the links and carry rollers 21, which engage notches 22 in the sprocket wheels 15, the links of the chain entering between the flanges of said sprocket wheels. The rollers 21 also serve to support the carrier chains on trackways 23 which are employed over the long tanks,—no trackways being necessary to support the carrier while it is passing over the shorter tanks. The hinge pins 18 are also provided at their inner ends with extensions 25, on which the cross bars 10 are supported. Each cross bar may conveniently consist of a short section of pipe, notched at its respective ends to permit it to be readily placed upon the extensions 25 of the hinge pins.

25 As before stated, the cross bars 10 serve as a means of attachment of the workholders with the carrier. Any suitable work holder 26 may be used and is provided with a shank 27 provided at its upper end with a hook 28 to engage the cross bar 10. In order to prevent lateral displacement of the hook 28 on the cross bar, collars 29 may be secured to said cross bar at respective sides of the hook.

While I prefer to provide all of the hinge pins of the carrier chains with the extensions 25 for the reception of cross bars 10, it will of course be understood that only such number of cross bars and work holders will be employed as may be desired by the operator.

40 Certain of the tanks will be provided with anode plates as usual in the art of electro-plating, while the work will constitute the cathode.

In order to provide suitable electrical connection with the work, conductor bars 30 are secured upon a suitable wooden frame on the tanks and contact brushes 31 are secured to the shank of the work holder and adapted to wipe against said conductor bars,—the shank 50 of the work holder being constructed or covered with metal in order that it shall constitute an electrical conductor from the bars 30 to the work.

Various slight changes might be made in 55 the details of construction of my invention without departing from the spirit thereof or limiting its scope and hence I do not wish to limit myself to the precise details herein set forth.

60 Having fully described my invention, what I claim as new and desire to secure by Letters Patent is:

1. In a plating apparatus, the combination with two series of tanks, one series disposed 65 above the other, of an endless carrier, means

for causing said carrier to travel over both series of tanks, means for suspending work holders from said carrier, and means for causing the carrier to rise and descend to dip the work successively in the tanks of the upper 70 series and then to dip the work successively in the tanks of the other series when the work carried by the carrier is traveling toward the starting point, whereby the return travel of the carrier can be utilized in the plating operations. 75

2. In an apparatus of the character described, the combination of two parallel carrier chains, wheels on the pins connecting the links of said chain, trackways on which said 80 wheels run, a tank below said trackways, cross bars mounted at their ends on connecting pins of the respective carriers, work holders having shanks hung on said cross bars, and means for preventing lateral displacement of 85 the work holder shanks on the cross bars.

3. In an apparatus of the character described, the combination with parallel carrier chains, cross bars removably mounted at their ends on pins of the respective carrier 90 chains, work holders, and shanks for said work holders having hooks removably supported on said cross bars.

4. In an apparatus of the character described, the combination with wheels having 95 lateral flanges and a central peripheral flange, of a carrier chain, rollers on the pins of the carrier chain to run on the lateral flanges of the wheels, collars on said chain to run on the central flanges of the wheels, a 100 sprocket wheel having recesses to receive the rollers on carrier chain, and means for connecting a work holder with the carrier chain.

5. In an apparatus of the character described, the combination with two carrier 105 chains and wheels over which said chains pass, of cross bars removably mounted on pins of said chains at intervals, and work holders suspended from said cross bars.

6. In an apparatus of the character described, the combination with two carrier chains, each comprising links connected by hinge pins, said pins having inward extensions, and wheels over which said chains pass, of 115 cross bars mounted at their ends on the inward extensions of the hinge pins of the two chains, and work holders suspended from said cross bars.

7. In an apparatus of the character described, the combination with a series of 120 tanks and a flexible carrier over the same, of work holders, each having a shank connected with the carrier, means for raising and lowering the carrier, conductor bars over said tanks, and brushes carried by the shank of the 125 work holder to wipe against said conductor bars.

8. In an apparatus of the character described, the combination with a tank and anode plates therein, of a carrier to travel 130

over the tank, trackways on said tank, rollers on the carrier to run on said trackways, means for suspending work from said carrier, means for raising and lowering the carrier to raise and lower the work, conductor bars supported over the tank, and brushes on the work-supporting means and adapted to wipe against said conductor bars.

In testimony whereof, I have signed this specification in the presence of two subscribing witnesses.

DAVID FELIX BRODERICK.
